UNITED STATES PATENT OFFICE.

BERNARD WILMSEN, OF PHILADELPHIA, PENNSYLVANIA.

ORNAMENT FOR CHRISTMAS TREES, DECORATIONS, &c.

1,217,675.

Specification of Letters Patent. Patented Feb. 27, 1917.

Application filed October 21, 1916. Serial No. 126,873.

To all whom it may concern:

Be it known that I, BERNARD WILMSEN, a citizen of the United States, residing in the city and county of Philadelphia, State 5 of Pennsylvania, have invented a new and useful Ornament for Christmas Trees, Decorations, &c., of which the following is a specification.

My invention consists of an ornament simulating a bell for Christmas trees, decorations, etc., the same being composed of a body of paper, or paper stock, such as cardboard or the like, pressed into the shape of said body and having a coating on the exterior 10 thereof for reinforcing or stiffening and strengthening purposes and giving to said body an appearance of heavy solid material.

It consists also of novel means for securing a clapper to the bell, and other details of 20 construction as will be hereinafter set forth.

The invention is satisfactorily illustrated in the accompanying drawing, but the important instrumentalities thereof may be varied, and so it is to be understood that 25 the invention is not limited to the specific details shown and described.

Figure 1 represents a side elevation of an ornament embodying my invention.

Fig. 2 represents a vertical section thereof. 30 Fig. 3 represents a bottom plan view thereof.

Similar numerals of reference indicate corresponding parts in the figures.

Referring to the drawings:

35 1 designates the body of the device, the same being of the form of a bell, it being constructed of a piece of paper, such as cardboard or other paper, stock or material stamped, struck-up or otherwise pressed into 40 the shape of the bell.

The exterior surface of the body has thereon the coating 2 which may be of saw-dust or other granulated or powdered wood, intermixed with adhesive material forming a 45 compact mass which is spread over and on said surface and caused to adhere firmly thereto, and when dry serves as a covering of wood to reinforce said body, and consequently stiffen and strengthen the same, said

50 coating being also of vastly greater firmness and stability than paper, and so is enabled to endure blows and usage without being fractured or broken, and preserves the body of the bell though the latter is made of the 55 lighter and pliable material.

The coating also covers and conceals the

buckling or crimping to which the paper is subjected while being pressed into shape and imparts to the bell the appearance of a heavy and solid material simulating a metallic bell 60 in which buckling or crimping does not exist, with the other advantages set forth as above. The crimps on the body also serve to impart strength primarily to said body as shaped.

65 3 designates the bell clapper, the same consisting of the head or hammer 4, and the piece 5 of wire or other flexible material. 6 designates the hanger of the bell, the same being adapted to have the loop 7 of ribbon, 70 tape, cord, etc., connected therewith for suspending the bell at the place of service, said hanger consisting of a piece of suitable metal or material bent into the form of the eye or ring 8 to which said loop is secured, and the legs 9 extending from said eye, said legs passing through an opening in the top wall of the body of the bell and spread under said wall, thus retaining the hanger in position.

75 The upper end of the piece 5 of the clapper is passed through said opening in the top wall of the body of the bell and wound or twisted around the ring as at 10, and so said piece 5 and consequently the hammer or head 4 is 80 sustained in a simple, convenient and inexpensive manner.

Having thus described my invention what I claim as new and desire to secure by Letters Patent, is;

90 1. An ornament for the purpose stated consisting of a struck-up body of paper simulating a bell, and a granular coating of comparatively hard material on the exterior surface thereof.

95 2. An ornament for the purpose stated consisting of a struck-up crimped body of paper simulating a bell, and a hard coating on the exterior surface thereof composed of material in granular form, and an adhesive intermixed therewith, said coating also covering the crimps on said surface.

100 3. An ornament for the purpose stated consisting of a body simulating a bell, a clapper, and means for connecting the latter to said body consisting of a piece of pliable material carrying said clapper, and a ring like member on the exterior member which is connectible with the top wall of said body and has said piece attached thereto 110 and pendant therefrom.

4. An ornament for the purpose stated

consisting of a body simulating a bell and having on its exterior a coating of hard material, a clapper, and means for connecting the latter to said body consisting of a piece 5 of pliable material which carries said clapper suspended therefrom, and having its upper end passing through the top wall of said body, and a ring-like member on the exterior of said top wall, said member having legs which engage said wall and are adapted 10 to secure said member thereto, the upper end of said piece being attached to said ring-like member.

BERNARD WILMSEN.
